UNITED STATES PATENT OFFICE.

GEORGES ANTOINE MARIE ARNAUD, OF PARIS, FRANCE.

CENTRIFUGAL RUNNER-MILL.

SPECIFICATION forming part of Letters Patent No. 499,083, dated June 6, 1893.

Application filed December 3, 1892. Serial No. 454,006. (No model.) Patented in France May 11, 1892, No. 221,548.

To all whom it may concern:

Be it known that I, GEORGES ANTOINE MARIE ARNAUD, a citizen of the Republic of France, residing in Paris, France, have invented a new and useful Centrifugal Runner-Mill, (for which I have obtained a French patent, No. 221,548, dated May 11, 1892,) of which the following is a specification.

The improvements forming the object of the present invention enable the weight of the crushing devices to be utilized, and at the same time the power communicated by centrifugal force to all machines partaking of rotary motion and which is usually wasted, is by these improvements caused to add to the useful effect of the machine. With this object I employ an arrangement intermediate between that of a mill with vertical runners working on a horizontal axis (Chilian mill) and that of the horizontal mills with horizontal runners working on a vertical axis (Huntingdon mill).

An example of a mill constructed according to my invention is represented in the accompanying drawings in which:—

Figure 1 represents a vertical section taken through the axis of the mill the section through the runner on the left hand being taken on the line 1. 2. 3 Fig. 3. the right hand runner being removed and one of the rakes or shovels brought forward into the plane of the section. Fig. 2 represents the mill in plan. Fig. 3 represents one of the runners in front elevation. Fig. 4 is a detail illustrating the arrangement of the shaft and bearings of one of the runners being curved at right angles to the section in Fig. 1 the caps of the bearings being removed. Fig. 5 represents a detail in vertical section taken along the line 40 6—7 Fig. 2. Fig. 6 is a diagram illustrating the principle of the action.

As represented in Figs. 1 and 2 of the drawings a gang or series of four crushing cylinders or runners B is arranged around a vertical shaft A driven by bevel gear placed underneath the mill and transmitting motion to the said runners by means of a driver or frame C provided with eight arms as represented in the illustration. I do not limit myself to the number of runners any number of which may be employed.

The axle or shaft b of each runner is inclined preferably at an angle of thirty degrees at first when the steel ring or bed is not yet covered with ore and the steel tires or 55 wearing surfaces of the runners are new. After a certain amount of wear this angle is reduced by about two or three degrees. The shafts b of the runners are supported in long bearings b' of cast steel lined with white metal. 60 The bearings are pivoted upon two journals b³ so as to enable the angle or inclination of the shaft to change during the working of the runners and enable the latter to rise and ride over any obstacles that may be met with at 65 the same time propelling them in their movement over the annular steel bed or die D. The said journals b³ work in cast iron boxes guided in each of the four pairs of arms of the driver C. The bearings as well as the shafts 70 of the runners are provided with a suitable number of annular ribs and grooves b⁵ for the purpose of resisting the tendency of the centrifugal force to displace the runners and move them away radially from the central shaft or 75 axis of the mill. The thrust bearings diminish the friction and the risk of heating which the great pressure would be liable to produce if sustained by a single shoulder or washer, the pressure being distributed over a large area 80 of surface and the lubricant being retained in the grooves so that it cannot be completely driven out by the centrifugal force. The combination of the four runners constituting an equivalent to the pendulums of a centrifugal governor a certain amount of force is applied in a vertical direction to the vertical shaft A tending to tear it out of its bearings and draw it upward until the shafts b of the runners assume a horizontal position. In order 85 to resist this tendency without augmenting the passive resistance the lower extremity of the said shaft works in a footstep or thrust bearing a of white metal and is provided with a certain number of annular 95 grooves a' engaging with corresponding ribs and grooves in the footstep bearing for the purpose of distributing the axial pressure over a large area of surface as hereinbefore explained with reference to the shafts of the 100 runners. The runners B may be made hollow and be filled with melted lead introduced

- through orifices b^6 provided for this purpose and capable of being closed by tight fitting plugs or covers. Under these conditions and on considering what takes place in the working of a mill constructed as represented in the accompanying drawings the following conclusions will be arrived at as will be easily understood by referring to the diagram Fig. 6.
- Assuming that the shaft A rotates at the rate of fifty revolutions that the weight P of the runner B is five hundred kilos and that the mean radius of rotation of the stones about the shaft A is eighty-two centimeters it will be readily ascertained by calculation that the value of the centrifugal force F is equal to eleven hundred and twenty kilos. The parallelogram of forces resulting from centrifugal force (F) and gravity (P) applied at the center of the runner can then be drawn.
- Upon the diagonal O R of this parallelogram it is easy to construct the parallelogram of the forces applied in the two directions in question namely:—(first,) the direction of the line O N perpendicular to the acting surface of the runner or in other words the force available for crushing and (second,) the direction of the line O O' or axis of the runner being in a direction in which a part of the centrifugal force is lost. It then appears that the force lost in the direction of the axis amounts to seven hundred and twenty kilos this being the effort resisted by the thrust bearings while the force N with which the runner is pressed against the bed amounts to about one thousand kilos. In other words the useful effect of ordinary weighted runners is doubled by means of this arrangement without increasing the motive power required.
- The crushing cylinders or runners are made with a cast iron hub B and steel tires or wearing rings b^7 fixed by pine blocks b^8 tightened by means of steel wedges b^9 driven into the wood. The wearing rings are provided with a projection b^{10} formed in casting and which prevents them from being thrown off by centrifugal force. I do not limit myself to this particular form of the runners as they may be constructed in any other ordinary or suitable manner. The steel ring die or bed D made in one piece is of rectangular shape in transverse section and its form is that generated by this rectangle the long side of which is inclined at an angle of thirty degrees with a horizontal line the said rectangle being revolved in a circle about a vertical axis. The ring bed D is maintained by wooden blocks d.
- In order to compensate for wear and remedy the disadvantage which would result when the surfaces of the runners and of the bed become worn away and cease to come together properly the following operation is performed which may be divided into two parts, namely: first, lowering the driver or propelling frame C in a vertical direction upon the central shaft of the mill; secondly, displacing the pivots or journals b^3 of the bear-

ings b' of the runner shafts in a horizontal direction by moving them away from the axis of the mill. These two movements are produced as next hereinafter described.

First. The frame or driver C is not permanently keyed upon the central shaft but slides upon a flat-sided portion c' of this shaft, so as to admit of vertical adjustment of the driver. The shaft is screw-threaded, at each side of the flat-sided portion. The driver is retained in position vertically by two nuts c^2 c^3 screwed upon the shaft so as to enable the position of the driver to be accurately adjusted. The nut c^2 placed underneath supports the weight of the driver and forms a stop, and the nut c^3 resists the tendency of the driver to rise due to centrifugal force in working. These nuts are secured by nut locks c^4 or in any other suitable manner.

Second. The displacement of the journals b^3 in a horizontal plane in order to move them away from the axis of the mill in proportion to the wear is produced as follows: The said journals b^3 work in cast iron boxes b^4 of rectangular form capable of sliding in the forked arms c^5 of the driver C as represented on the right hand in Fig. 1 of the annexed drawings. The hole for the reception of the journals b^3 is eccentric or placed near one end of the rectangular block b^4 .

On commencing to work the mill with new wearing rings b^7 and a new steel bed D the part x being the narrowest is placed nearest to the axis of the mill and bears directly against the central part of the driver C. When the wearing ring b^7 and the bed D become worn away after working for a certain time a number of plates of sheet metal of about one millimeter in thickness are successively introduced between C and b^4 until the journals b^3 are removed from the central shaft to a sufficient distance to enable the block b^4 when reversed or turned round end for end and replaced without the plates to retain the journal at the same distance from the central shaft. This bearing b^4 may now be turned round so as to bring the end x' against C after which as the wearing away of the ring or tire and the bed continues the thin plates are again successively introduced at the back of the block between x and C. The block b^4 and the thin plates are tightened up against C by a screw b^{12} working in a strap or cover b^{11} . The ore is introduced into the mill through a number of hoppers T and the crushed product is discharged through sieves t arranged in pairs between the hoppers. The stirring and distribution of the ore as well as the discharge of the mud or slime are facilitated by the action of agitators or shovels H of special form as represented in Figs. 1 and 2 of the drawings being attached to a revolving cast iron cross frame keyed upon the central shaft A at k above the driver C. The form of the agitators H as shown in the drawings is such as to draw the mud and ore into the track of the runners at the same time producing owing

to the speed a wave which in passing before the sieves facilitates the discharge of the finer part of the mud.

In order to obviate the inconvenience resulting from an accidental obstruction produced either by a stone or by a piece of metal accidentally falling onto the bed the fork shaped piece h carrying the agitator is connected to the driving arm h' by a single bolt h^2 being retained in position by a wood pin h^3 which when abnormal resistance is met with gives way or is sheared off and allows the rake to turn back upon the bolt h^2 .

The mill runs at great speed or about fifty revolutions per minute. Light runners are employed but by utilizing the centrifugal force their action is rendered equivalent to that of runners of twice the weight in a vertical mill.

The arrangement being perfectly symmetrical the machine resists in itself the different strains to which it is subjected. Owing to its speed it acquires an enormous momentum which enables it to overcome without additional power resistances such as might be caused by small heaps of ore collecting in front of the runners or by a tool or bolt falling accidentally onto the bed. For treating ores of gold it does not present the disadvantage of the vertical mills with short arms and consequently small diameter of track with a width of from nine to ten inches which act partly by torsion and partly by crushing owing to the difference between the diameters of the inner and outer parts of the track. This crushing impedes the amalgamation by forging the gold. Attempts have been made to improve these mills by increasing the diameter of the track of the runners and at the same time reducing the width of their wearing surfaces. The symmetrical or regular arrangement of the discharge openings and hoppers also has some influence on the working of the apparatus which owing to the relative lightness of the runners is capable of attaining a very high tangential speed thereby increasing their useful effect at the same time as the distance traversed or extent of crushing surface.

I do not limit myself as to the details of construction hereinbefore described with reference to the drawings; but

What I claim is—

1. In mills, the combination of a central vertical shaft and a thrust bearing or like means for resisting vertical movement of the shaft, with centrifugal inclined pivoted runners, and an inclined annular bed, substantially as and for the purpose set forth. 55

2. In mills, the combination of a central vertical shaft and means for resisting vertical movement of the shaft, with a driver adjustably secured to the said shaft, centrifugal inclined runners, bearings for the shafts of the runners, adjustable boxes in the said driver 65 and in which the said bearings are journaled and an inclined annular bed, all substantially as and for the purposes set forth.

3. In mills, the combination of a central vertical shaft provided with a flat sided portion, and screw-threads at each side thereof and means for resisting vertical movement of the shaft, with a driver fitted upon the flat-sided part of the shaft, nuts screwed upon the said threaded parts, centrifugal inclined 70 runners pivoted in adjustable bearing boxes carried by the said driver, and an annular inclined bed, all substantially as and for the purposes set forth.

4. In mills, the combination of a central vertical shaft, means for resisting a vertical movement of the shaft, and a driver adjustably secured to the shaft and provided with forked arms carrying adjustable boxes provided with eccentric holes, with inclined runners and bearings for the shafts of the said runners, the said bearings being provided with journals to be received by the eccentric holes in the said boxes all substantially as and for the purposes set forth. 85

5. In mills with centrifugal runners the combination of a central shaft, and a frame having projecting arms keyed on the shaft, with rakes attached to the extremity of the said arms by metal bolts, and retained in position by wooden pins adapted to give way under abnormal resistance, substantially as 95 and for the purposes set forth.

In testimony whereof I have signed my name to this specification in the presence of 100 two subscribing witnesses.

GEORGES ANTOINE MARIE ARNAUD.
